BOTTOM RAIL FOR VENETIAN BLINDS

Irving Jablin, Brooklyn, N. Y.

Application October 19, 1945, Serial No. 623,287

5 Claims. (Cl. 160—173)

1

The invention relates to a bottom rail for Venetian blinds and other window shades, or curtains that require more or less added weight as an aid in lowering them and for holding them under requisite tension to prevent billowing and flapping from being wind blown.

As applied to a Venetian blind, the rail provides anchorage for the slat-supporting tapes and the cords for raising the blind and, in order to give the rail a pleasing exterior appearance and finish, it is desirable to conceal the points of attachment from view. This is accomplished by giving the rail the form of a chambered casing, die-formed of light sheet metal and provided with openings through which the tapes and cords pass neatly and cleanly to the interior thereof, where they are secured.

For convenience in securing the tapes and cords within the casing, it is given the form of a flat tube of approximately rectangular cross section, split lengthwise into two opposing trough-like sections, which are separable to give ready access to the interior and are suitably shaped to be snapped together and so held by their own resilience.

To provide anchorage for the tapes and cords within the casing and at the same time stiffen and strengthen it and prevent bending or collapse under strain, it is reinforced interiorly by a core or filler of wood or other suitable material, sections of which preferably extend inward from each end of the casing to the point where the tapes and cords enter and are there given a terminal formation suitable for operatively attaching the tapes and cords thereto.

In addition to the foregoing, other structural features not specially mentioned above will be brought to attention in the detail description that follows.

A construction suitable for carrying the invention into effect is illustrated in the accompanying drawing, but, it will be understood, that no limitations are intended by this showing, other than are imposed by the appended claims.

In the drawing—

Fig. 1 is a view in perspective, showing the lower portion of a Venetian blind, with the improved bottom rail attached thereto.

Fig. 2 is a central longitudinal section of the rail, showing the blind-supporting tapes and cords secured to the wood filler sections within the same.

Fig. 3 is an exploded view in cross section of the bottom rail sections and wood filler.

2

Fig. 4 shows the same parts in assembled relation, and

Fig. 5 is a plan view of one of the wood fillers. Referring now to the drawing, 1, 1 indicate several of the slats that form the lower portion of a Venetian blind, 2, 2 are the usual tapes that support the slats and 3, 3 are the cords ordinarily employed for raising and lowering the blind.

10 The bottom rail is indicated at 4 and consists of a two-part shell-like casing, in the form of a flat tube, divided lengthwise and suitably reinforced at the ends by a core or filler.

15 The rail sections 5, 5 are shaped up by forming dies from thin sheet metal but may be otherwise made from any material preferred.

20 As shown, the rail is approximately rectangular in cross section, with slightly rounded corners, and while this form meets all practical requirements, it may be varied more or less, if desired.

25 The meeting edges of the rail sections are beaded, as indicated at 6, 6, and when assembled, the beads of one section overlap and grip the beads of the other section, securely but yieldingly interlocking the two sections together. In assembling the sections, the resilience of the metal is such as to enable them to be snapped together and they will be thus spring-held, without the aid of other fastenings. In addition to 30 serving the above described useful purpose, the beads break the plain surface of the rail and give it an ornamental finish.

35 The upper rail section is provided with slots 7, 7 and openings 8, 8, through which the slat-supporting tapes 2, 2 and the blind raising and lowering cords 3, 3 are entered in the rail.

40 Anchorage for the tapes and cords within the rail is provided by shaped portions of the end reinforcements 9, 9, which are preferably of wood and conform in cross section approximately to the interior of the rail, including the beaded formation, which is followed in shaping these cores or fillers, as indicated at 10 (see Figs. 3 and 4).

45 The reinforcements 9, 9 extend inward from opposite ends of the rail to the point where the tapes and cords enter the same and are there reduced, as indicated at 11, to extend through and provide clearance for a loop 12 of each of the tapes, which may be additionally secured by a 50 tack or two, indicated at 13. The reduced end portions 11, 11 are also provided with openings 14 for the passage of the cords, the knotted ends 15 of which are drawn and held in counterbored portions 16 of such openings, as shown in Figs. 55 2 and 4.

For added appearance and finish, the open ends of the tubular bottom rail may be closed by caps 17, which are tightly fitted to be self-holding.

As the construction, operation and many important advantages of the invention will be apparent from the foregoing, it will not be necessary to further describe the same.

I claim:

1. A bottom rail for a Venetian blind, formed in sections extending lengthwise of the rail and secured together by integral snap fastener formations at the meeting edges of the sections and a core within the rail providing anchorage for the blind-supporting tapes and cords. 10
2. A bottom rail for a Venetian blind, formed in sections extending lengthwise of the rail and secured together by integral snap fastener formations at the meeting edges of the sections and a sectional core within the rail to which the blind-supporting tapes and cords are secured. 20
3. A bottom rail for a Venetian blind, formed in sections extending lengthwise of the rail and secured together by integral snap fastener for-

mations at the meeting edges of the sections and a sectional core within the rail to which the blind-supporting tapes and cords are secured, the sections of the core being spaced apart to position the sections thereof at opposite ends of the rail.

4. A bottom rail for a Venetian blind, formed in sections secured together by integral snap fastener formations at their meeting edges, one of the sections being slotted and apertured for the passage of the blind-supporting tapes and cords and a sectional core within the rail to which the tapes and cords are secured.

5. A bottom rail for a Venetian blind, formed in sections secured together by integral snap fastener formations at their meeting edges, one of the sections being slotted and apertured for the passage of the blind-supporting tapes and cords and a sectional core within the rail conforming approximately in cross section to the interior thereof and having end portions cut away to provide clearance for the aforesaid tapes and cords which are attached thereto.

IRVING JABLIN.
